UNITED STATES PATENT OFFICE

148,308

DESIGN FOR A RAILWAY CAR

Otto A. Kuhler, Blauvelt, N. Y., assignor to
American Car and Foundry Company, New
York, N. Y., a corporation of New Jersey

Application March 9, 1946, Serial No. 127,318

Term of patent 14 years

(Cl. D66—1)

To all whom it may concern:

Be it known that I, Otto A. Kuhler, a citizen of the United States, residing in Blauvelt, in the county of Rockland, State of New York, have invented a new, original, and ornamental Design for Railway Car, of which the following is a specification, reference being had to the accompanying drawings, and which form a part thereof.

Figure 1 represents a perspective view of the rear end of the railway car;

Fig. 2 discloses a plan view of the railway car, and

Fig. 3 discloses an elevational view of the car.

The present design comprises as the principal and dominating features thereof those portions

of the drawings shown in full black lines. Both sides of the design are similar, hence only one side has been shown in detail.

I claim:

The ornamental design for a railway car, substantially as shown and described.

OTTO A. KUHLER.
